The ornamental design for a tape printing machine, as shown and described.

DESCRIPTION

FIG. 1 is a front view of a tape printing machine;

FIG. 2 is a top view thereof;

FIG. 3 is right-side view thereof;

FIG. 4 is a left-side view thereof;

FIG. 5 is a rear view thereof;

FIG. 6 is a bottom view thereof;

FIG. 7 is a front, left-side perspective view thereof;

FIG. 8 is a front, right-side perspective view thereof; and,

FIG. 9 is a front view of the tape printing machine in an alternate configuration.

The broken lines depict environmental subject matter only and form no part of the claimed design.
